INVENTOR,

Charles J. Jorgensen
By H. G. Underwood
ATTORNEY.

UNITED STATES PATENT OFFICE.

CHARLES J. JORGENSEN, OF MILWAUKEE, WISCONSIN.

DESIGN FOR A PICTURE OR ANALOGOUS FRAME.

SPECIFICATION forming part of Design No. 22,292, dated March 14, 1893.

Application filed January 3, 1893. Serial No. 457,163. Term of patent 3½ years.

To all whom it may concern:

Be it known that I, CHARLES J. JORGENSEN, a citizen of the United States, residing at Milwaukee, in the county of Milwaukee and State 5 of Wisconsin, have invented and produced a new and original Design for Ornamental Frames; and I do hereby declare the following to be a full, clear, and exact description of the same, reference being had to the accompanying drawing, forming a part thereof.

My design is intended to be materialized in or upon a picture and analogous frame designed for holding any suitable object, such as a picture, photograph, calendar, advertisement, or any other article such as is now exhibited within a frame, and it consists, primarily, of an oblong inner ornamental border, surrounded by irregular ornamental projections, and extensions, making an original ornamental contour, and secondly of the ornamentation in relief, or designed so as to appear in relief, on the surface of the design included in said ornamental contour. At each upper corner of the described inner border 5 are ornamental scrolls, of a general double-ogee form, the lower portions of which extend down alongside the side edges of the said inner border and which are ornamented with foliated projections, while the upper ends of these scrolls are ornamented with a series of laminated petals, varying in size, and connected continuously together, with practically oval depressions in each petal, arranged radially about the said upper ends of the scrolls. Connecting with the upper end of the just described left-hand scroll is another scroll of similar double-ogee shape, extending along above the upper line of the first described oblong inner border, in a generally upward oblique direction, and provided with a series of foliations of varying sizes, each leaf being centrally provided with practically oval depressions. The forward or right-hand end of this last described scroll terminates in a bunch of conventionalized leaves, from which extends, to the left, a branch containing leaves

and a blossom, the last leaf and the blossom interrupting the continuity of the upper lines of the described oblong inner border, and the said blossom extending a little to the left of the center of the same. An ornamental semi-circular scroll fills up the space between the right hand end of the upper obliquely arranged scroll, and the described right-hand upper corner scroll, with whose upper end it blends. 55 The upper ends of the upper corner scrolls are larger than their lower ends, the lower end of the right hand scroll terminating in an enrolled curve, and the lower end of the left-hand scroll terminating in a pointed trefoil. 60

The lower right-hand corner of the design is ornamented with the large inrolled end of another generally double-ogee shaped scroll, extending to the left, beneath the oblong inner border and terminating in a smaller inrolled end, this scroll being foliated, and provided with lower shoots or branches, having obtuse ends, while the lower left-hand corner of the design is ornamented with a scroll of generally semi-circular form, having inrolled 65 ends, and a series of inner or upper foliated shoots or branches of different lengths, filling up the space between the main corner scroll and the angle of the inner oblong border, at its lower left corner. The exterior of this 70 lower left-hand scroll is ornamented with a series of conventionalized shell-like figures, of varying sizes, and between the right-hand end of this lower left-hand corner scroll and the left-hand end of the lower right-hand scroll, there is a conventionalized blossom 75 with central oval depression.

Having thus described my design, what I claim is—

The design for picture and analogous 80 frames, substantially as shown and described.

In testimony whereof I affix my signature in presence of two witnesses.

CHARLES J. JORGENSEN.

Witnesses:

H. G. UNDERWOOD,
JOHN E. WILES.
